(57) **CLAIM**

The ornamental design for an air treatment or purification apparatus, as shown and described.

DESCRIPTION

FIG. 1 is a perspective view of the front from above right side of the air treatment or purification apparatus, showing our new ornamental design;

FIG. 2 is a perspective view of the rear from above left side thereof;

FIG. 3 is a front elevational view thereof;

FIG. 4 is a right side elevational view thereof, the left side elevational view being a mirror image thereof;

FIG. 5 is a rear elevational view thereof;

FIG. 6 is a top plan view thereof; and,

FIG. 7 is a bottom plan view thereof.

The broken line showing is included for the purpose of illustrating and forms no part of the claimed design.
